UNITED STATES PATENT OFFICE.

HENRY W. NAGEL, OF CHARLESTON, SOUTH CAROLINA.

SEWER-TRAP.

1,351,677.

Specification of Letters Patent. Patented Aug. 31, 1920.

Application filed January 20, 1919. Serial No. 272,070.

To all whom it may concern:

Be it known that I, HENRY W. NAGEL, a citizen of the United States, residing at Charleston, in the county of Charleston, 5 State of South Carolina, have invented certain new and useful Improvements in Sewer-Traps; and I do hereby declare the following to be a full, clear, and exact description of the invention, such as will enable others skilled in the art to which it 10 pertains to make and use the same.

This invention relates to new and useful improvements in sewer devices and particularly to sewer traps.

15 One object of the present invention is to provide a novel and improved trap for use in gutters which will readily permit the exit of water and trash, but which will prevent the escape of the gases from the sewage.

20 Another object is to provide a novel and improved door for the trap which will be easily opened by the water from the gutter, but which will immediately and effectively close to prevent the escape of the sewer 25 gases.

A further object resides in the provision of novel means for insuring the closing of the door should the same be opened to a slight extent and have a tendency to remain 30 in such position.

Other objects and advantages will be apparent from the following description when taken in connection with the accompanying drawing.

35 In the drawing:

Figure 1 is a top plan view of the trap in position in a gutter.

Fig. 2 is a vertical sectional view taken on the line 2—2 of Fig. 1.

40 Fig. 3 is a horizontal sectional view taken on the line 3—3 of Fig. 2, looking upwardly in the direction of the arrows to show the manner of pivotally mounting the door.

Fig. 4 is a horizontal sectional view taken 45 on the line 4—4 of Fig. 2, looking downwardly in the direction of the arrows to show the manner in which the curved guard plate is set in the casing of the trap.

Referring particularly to the accompanying drawing, 10 represents a metal casing the upper and lower ends of which are open. Seated on the ledge 11, in the upper end of the casing, is a metal grating 12, which is disposed on a level with, or slightly below 55 the level of the gutter. Two opposite sides of the casing have their lower portions cut

out to form the V-shaped notches 13, and projecting inwardly from each of these sides, at points slightly inwardly of the apices of the notches, are the pivot pins 14. 60 In each of said sides, and in the upper portion thereof, there is formed the curved and downwardly extending shoulder 15, the lower end of which communicates with the upper end of the groove 16. A curved guard plate 17 is slipped downwardly and inwardly on these shoulders and has the side edges, at their lower portions engaged in said grooves, whereby said guard plate will be firmly and properly held in place within 70 the casing to direct the water and other material from the gutter, through the casing.

A door 18 is disposed obliquely in the casing, the lower end engaging with the lower edge of the wall at the outer end of the 75 notch, while the upper end rests against the upper portion of the opposite wall. A narrow plate 19 is bolted to the lower face of the upper end of the door, and in the lower edge of this plate there is formed a longitudinal groove 20, the end portions of which engage with the pins 14, whereby the door is pivotally hung on said pins, but capable of being quickly and easily removed by swinging the door into vertical position and 80 then lifting the door from the pins. Connected to the upper end of the bolt 21, which holds the plate 19 on the door, is a coil or other spring 22, the upper end of which is adapted to engage with the lower face of 85 the guard plate 17 to serve the purpose of a buffer, and to impart an initial closing movement to the door.

The spring 22 also serves to prevent the door from swinging into a vertical position 95 which would render it liable to unseating from the pins 14. It will be readily understood that under the weight and pressure of the water against the door, the spring is under compression against the guard plate 100 17, and when this weight is released the spring will expand and start the door toward closed position.

It will also be noted that the lower portions of the side edges of the door extend 105 outwardly through the notches 13 and bear against the upper walls of said notches when said door is in normal closed position. The shoulders 23, formed by these lateral extensions of the door, effectively prevent displacement of the door from the supporting pivot pins. The shoulders are, however, so

formed that when the guard plate is removed the door can be swung into a vertical position, when the door can be lifted from the pins, and then by a forward bodily movement of the door, the same can be slipped downwardly through the lower open end of the casing. When the guard plate is in proper position, the door is prevented from swinging into this vertical position, and thus the door is effectively held in pivotal position within the casing.

It will be noted that the brick-work of the sewer entrance 24, below the trap, is built to incline in an undercut manner thereby permitting the door to easily swing into its full open position.

What is claimed is:

A sewer trap comprising an open-ended casing having curved grooves in the inner faces of two of its opposite walls, a curved guard plate engaged in said grooves and extending into the casing, the lower por-

tions of said grooved walls being cut out and formed with stop shoulders, inwardly extending pins carried by said walls, and a door having an inner thickened end portion formed with a longitudinal groove arranged to receive the said pins and whereby said door is pivotally supported in the casing, the said thickened portion of the door lying beneath the curved guard plate, and a spring carried by said thickened portion and arranged to be compressed against said guard plate when the door is swung open and to expand to impart an initial closing movement to the door when pressure is released from the door.

In testimony whereof I affix my signature in the presence of two witnesses.

HENRY W. NAGEL.
